UNITED STATES PATENT OFFICE

2,442,901

MATERIAL WORKING APPARATUS

Arthur M. Missbach, Riverside, Ill., assignor to
Western Electric Company, Incorporated, New
York, N. Y., a corporation of New York

Application August 9, 1945, Serial No. 609,879

13. Claims. (Cl. 164—13)

1

This invention relates to material working apparatus and more particularly to punch and die apparatus for perforating and trimming terminals projecting laterally from electrical resistors.

The invention is particularly useful in perforating and trimming flat type terminals projecting laterally from ceramic coated electrical resistors following the steps in the method of manufacturing resistors disclosed in application Serial No. 605,133, filed July 14, 1945, now U. S. Patent No. 2,427,417, granted September 16, 1947, to A. J. Prickett, which includes the step of removing from opposite flat surfaces of the terminals a ceramic coating which had been applied thereto to prevent oxidation of the surfaces of the terminals during the firing of the ceramic coating material. Generally, upon completion of the referred-to method, some ceramic coating remains on the edges of the projecting terminals, which still have to be rounded off at their outer ends and perforated so that wire may be threaded through the hole and soldered connections made.

An object of the present invention is to provide an efficient and practicable apparatus for working the above-referred-to terminal while attached to the resistor, whereby it is simultaneously perforated and trimmed around its edge to remove any ceramic coating thereon and its outer end rounded off.

In attaining this object, there is provided, in one embodiment of the invention, cooperating fixed and movable punch and die members for working the terminal while attached to the resistor, a resiliently mounted element substantially surrounding the fixed punch and normally positioned thereabove and shaped to form means for laterally guiding a terminal into position against a stop member thereon for working and, in cooperation with the fixed punch, a nest for supporting the terminal during its working. A movable air exhaust duct carried by the resiliently mounted terminal guide and nesting element is reciprocative upon a stationary air exhaust duct, whereby the two ducts are at all times in communication, the inlet of the movable duct being arranged and effective to constantly draw from the apparatus all materials trimmed from the edges of the terminal. In cooperation with the air exhaust duct, an air blast is connected to and passes through the fixed punch, which is effective to cause a heavier end portion, trimmed off the terminal, to be lifted off the fixed punch and carried away by the air exhaust system.

Other objects and advantages of this invention

2

will more fully appear from the following detailed description, taken in conjunction with the accompanying drawings, wherein

Fig. 1 is a fragmentary irregular vertical sectional view taken on the line 1—1 of Fig. 4 through the punch and die apparatus embodying the present invention, the apparatus being shown in its normal position with a cross section of a terminal nested thereon ready to be worked;

10. Fig. 2 is a fragmentary vertical sectional view, partly in elevation, taken on the line 2—2 of Fig. 4, the apparatus being shown in its normal position, similar to that of Fig. 1;

Fig. 3 is a fragmentary vertical sectional view, 15 similar to Fig. 1, showing the apparatus in a fully operated position and before the retraction of the movable die;

Fig. 4 is a plan view, partly in section, taken on the line 4—4 of Fig. 1 of that portion of the apparatus situated below the movable die; and

Fig. 5 is a plan view of one type of electrical resistor illustrating its terminals at opposite ends before and after being worked upon by the apparatus of this invention.

20. 25. As illustrated in the drawings, the punch and die apparatus embodying the features of this invention is operatively connected to a punch press, which may be of any usual type. Since it is not essential to a complete understanding of the invention, the punch press has not been illustrated, except those parts directly concerned with this invention, which consist of the following: A vertically reciprocative ram and a stationary bed 10 and 11, respectively (Fig. 1). Fixed to the top face of the bed 11 is a bolster plate 12, to which are affixed guide posts 13 that extend into apertures 14 in a reciprocative die and punch head 15. Secured to the top face of the bolster plate 12 is a punch 16, which, in the operation of the apparatus, cooperates with a die 17 fixed to and depending from the bottom face of the die and punch head 15, which is secured to and reciprocates with the ram 10 to work a terminal 18 projecting laterally from the resistor 20 (Figs. 2, 4 and 5). Surrounding and reciprocative on the upper vertical end of the fixed punch 16 is a resiliently mounted terminal guide and nesting member 21, which is guided in its movements by a pair of guide pins 22 (Fig. 4) secured to and depending from the nesting member 21 and at their lower ends slidably fitted in apertures 23 in the bolster plate 12. The nesting member 21 is resiliently supported in its upper normal position, as shown in Fig. 1, by a plurality of compression springs 24, bearing at opposite

ends on opposed faces of the member 21 and the bolster plate 12 and surrounding headed screws 25 secured to and depending from the member 21. Downwardly facing shoulders 26 are formed in the lower ends of apertures 27 in the bolster plate 12, in which the headed screws reciprocate, and against which the inner annular faces of the screw heads abut to limit the upward movement of the nesting member 21 to its normal position (Figs. 1 and 2).

It will be observed, referring to Figs. 1 and 2, that the member 21, when in its normal upper position, is above the upper face of the fixed punch 16, the distance being suitably greater than the thickness of the terminal 18 to be worked. This arrangement results from an upwardly extending rectangularly shaped portion 29 of the member 21 being formed with a horizontal irregularly shaped slot 30 in its upper face, which extends completely thereacross. The forward end of the member 21 and its upper portion 29, as viewed in Fig. 4, and the left end thereof, as viewed in Fig. 2, is formed with a vertical slot 31 which intercepts the slot 30 and in which the upper end of the fixed punch 16 freely fits. In the normal position of the member 21 (Figs. 1 and 2), the upper face of the fixed punch 16 lies in the plane of the bottom face of the slot 30. Thus, the vertical walls of the slots 30 and 31, in cooperation with the upper horizontal face of the punch 16 and the bottom face of the slot 30, provide a guide and nest for receiving the terminal 18 to be worked. A stop member 32 fixed to the member 21 and extending into the slot 30 serves to definitely position the terminal 18 longitudinally in the slot 30. As the terminal 18 is inserted into position, its outer end edge, which is square before being worked upon, abuts the stop member 32.

Carried by the resiliently mounted guiding and nesting member 21 is an air exhaust duct 35 (Figs. 2 and 4), having a tapered aperture 36 therein. At its smaller end, the walls of the aperture 36 are aligned with a tapered portion 37 of the slot 30 in the member 21 and the larger end of the aperture is at all times in communication with an aperture 38 in a stationary air exhaust duct 39 fixed to the bolster plate 12, which is connected to a suitable source of constant air suction (not shown). This air exhaust system serves to draw from the punch and die members 16 and 17 all ceramic and other materials trimmed from the edges of the terminal 18. Cooperating guideways and guides 42 and 43 on the ducts 35 and 39, respectively, serve to minimize air leakage between the ducts as the duct 35 is guided up and down on the duct 39 in the operation of the apparatus.

Fixed in a shouldered aperture 44 (Fig. 2) in the member 21 is one end of a tube 45 having its opposite end slidably fitted in an aperture 46 in the stationary punch 16. The aperture 46, at its lower end, communicates, by means of suitably arranged apertures 49 and 50, in the bolster plate 12, with a hose or pipe 51, which is connected to a suitable source of air pressure (not shown). A blast of air may thus be directed upwardly at a point in front of the stop member 32 and directly under a relatively heavy portion trimmed from the end of the terminal in providing the terminal with a rounded outer end. This blast of air is preferably intermittent, and controlled by means (not shown) from the movements of the ram 10, whereby, as the upper movable die 17 is retracted, the trimmed end portion of the terminal 18 is lifted from the punch 16 and above the stop member 32 whereat, by the action of the air exhaust,

it will be carried away through the ducts 35 and 39 along with all ceramic and other materials trimmed from the edges of the terminal.

Reciprocative in a die aperture 52 of the die 17 is a spring-pressed shouldered shedder 53, which, in the normal retracted position of the die 17 (Figs. 1 and 2) is pressed downwardly to its advanced position with its lower face in the plane of the lower face of the die by a pair of push pins 56 slidable through apertures in a pair of abutting plates 57 and 58 carried in shouldered recesses in the die 17 and the die and punch head 15, respectively. The push pins 56 are normally maintained in their lowered position, as shown in Figs. 1 and 2, by a backing plate 59 acted upon by a compression spring 60, the plate and spring being free to move in an aperture in the head 15. Carried in apertures in the shedder 53 and plate 57 is a shouldered perforator 63, which cooperates with a die aperture 64 in the fixed punch 16 to punch an aperture 65 (Fig. 5) in the terminal 18 simultaneously with the trimming of the terminal by the coaction of the die aperture 52 of the upper die 17 with the fixed lower punch 16. Suitable apertures are provided in the punch 16, bolster plate 12 and press bed 11 through which the punchings resulting in the aperture 65 are removed. It is to be understood that the dimensions of and clearances between the edges of the die aperture 52 and punch 16 are such that, in the downward stroke of the upper die 17, the metal of the terminal 18, at its free outer end, is sheared off to provide a rounded end and any ceramic and other materials on the edges of the terminal are trimmed away without appreciably trimming the metal thereat.

Extending upwardly from and fixed to the bolster plate 12 is a combined terminal guide and guard member 66 for the space between the co-operating punch and die members 16 and 17 (Figs. 2 and 4), which is slotted, as indicated at 67, in line with the slot 30 in the resiliently mounted terminal nesting member 21, the dimensions of the slot 67 and its arrangement being such that the terminal may be freely inserted into the nesting slot 30 and against the stop member 32, where it rests on top of the fixed punch 16. Also formed in the member 66 at each side and aligned therewith are two slots 68 for receiving terminals 50 on the resistor 20 other than the one terminal thereof to be worked, the arrangement of the slots 67 and 68 being such that resistors of different types and having more than one pair of terminals may have their terminals 18 worked upon.

In the operation of the punch and die apparatus, above described, a resistor 20, having a pair or more of laterally projecting terminals 18, is placed in position with one of its terminals inserted through the guide slot 67 in the guard member 66, with its outer end edge abutting the stop member 32, as clearly shown in Figs. 2 and 4. Thereafter, the ram 10 is caused, in a usual manner, to descend to the position shown in Fig. 63. In this movement of the ram 10, the lower face of the die 17 carried thereby engages the upper face of the resiliently mounted terminal nesting member 21 and depresses it against the action of the springs 24. Thus, the outer free end of the terminal 18 is rounded off and any ceramic material on the opposed edges of the terminal is trimmed off by the coaction of the edges of the die aperture 52 of the movable die 17 with those of the fixed punch 16 as the movable die moves below the plane of the upper end

face of the punch, as shown in Fig. 3. Simultaneously with this forming and trimming movement of the die 17, the lower faces of the perforator 63 and the shedder 53 are moved into engagement with the upper face of the terminal 18 remaining in a fixed position and as the perforator 63, which is fixed to and moves with the die 17, continues its movement to perforate the terminal, the shedder recedes into the die 17 against the action of the spring 60 to the position shown in Fig. 3. As the ram 10 again ascends to its normal position (Figs. 1 and 2), the spring-pressed nesting member 21 also moves upwardly to its normal position, limited by the headed screws 25 engaging the shoulders 26 of the apertures 27. Also during this latter movement of the ram 10, the spring-pressed shedder 53 returns to its normal position relative to the die 17, thus leaving the portion of the terminal 18 sheared off in forming its free outer rounded end lying on the upper face of the fixed punch 16, at which instant a blast of air directed through the aperture 44, in the manner previously described, lifts the sheared-off portion of the terminal above the stop member 32, whereupon it is carried away along with the ceramic and other particles trimmed from the terminal by the action of the air in the air exhaust system. It is to be noted that in the operative position of the die 17 (Fig. 3), wherein it abuts the upper face of the member 21, the slot 30 is closed and sealed across its top by the die 17, which serves to increase the effectiveness of the air exhaust system in removing ceramic and other particles from the apparatus.

What is claimed is:

1. In an article working apparatus, a stationary support, a fixed punch mounted thereon, an element so constructed and arranged relative to and cooperating with said punch to form a nest for receiving and supporting an article movable longitudinally thereinto prior to the tool's action, means for yieldably maintaining said element in a normal position relative to said punch to form said nest, a movable ram, and a die carried by said ram and cooperating with said punch to work the nested article.

2. In an article working apparatus, a stationary support, a fixed punch mounted thereon, an element substantially surrounding said punch, means for yieldably maintaining said element in a normal position relative to said punch to form, in cooperation with said punch, a nest for receiving and supporting an article movable longitudinally thereinto prior to the tool's action, a movable ram, and a die carried by said ram and cooperating with said punch to work the nested article.

3. In an article working apparatus, a stationary support, a fixed punch mounted thereon, an element substantially surrounding said punch, means for yieldably maintaining said element in a normal position relative to said punch to form, in cooperation with said punch, a nest for receiving and supporting an article movable longitudinally thereinto prior to the tool's action, a movable ram, and a die carried by said ram effective during its operative movement to cause movement of said element to permit the die, in cooperation with said punch, to work the nested article.

4. In an article working apparatus, a stationary support, a fixed punch mounted thereon, an element so constructed and arranged relative to and cooperating with said punch to form a nest for receiving and supporting an article mov-

able longitudinally thereinto, a stop member on said element for limiting the longitudinal movement of the article into said nest, means for yieldably maintaining said element in a normal position relative to said punch to form said nest, a movable ram, and a die carried by said ram cooperating with said punch to work the nested article.

5. In an article working apparatus, a stationary support, a fixed punch mounted thereon, an element extending around a plurality of sides of said punch and having a slot extending transversely thereof, said slot being open at one side of said punch, means for yieldably maintaining said element in a normal position relative to said punch to form a nest for receiving and supporting an article movable longitudinally thereinto, a movable ram, and a die carried by said ram and cooperating with said punch to work the nested article.

6. In an article working apparatus, a stationary base, a fixed punch mounted thereon, an element extending around a plurality of sides of said punch and having a slot open at each end extending transversely of said punch, means for resiliently elevating said element to a normal position above said punch whereby said slot and an upper end face of said punch form a nest for receiving and supporting an article, a movable ram, and a die carried by said ram and cooperating with said punch to work the nested article.

7. In an article working apparatus, a stationary base, a fixed punch mounted thereon, an element extending around a plurality of sides of said punch and having a slot extending transversely thereof, said slot being open at one side of said punch, means for resiliently elevating said element to a normal position above said punch to form a nest for receiving and supporting an article movable longitudinally thereinto, a movable ram, and a die carried by said ram for engaging and moving, during its operative movement, said element to permit the die, in cooperation with said punch, to work the nested article.

8. In an article working apparatus, a stationary support, a fixed punch mounted thereon, an element so constructed and arranged relative to and cooperating with said punch to form a nest open at opposite ends for receiving and supporting an article movable longitudinally thereinto from one end of said nest, means for yieldably maintaining said element in a normal position relative to said punch to form said nest, an air exhaust duct carried by said element communicating with said nest, a stationary air exhaust duct cooperating with said first duct and in constant communication therewith through which all waste material resulting from the working of the article is sucked, a movable ram, and a die carried by said ram and cooperating with said punch to work the article.

9. In an article working apparatus, a stationary base, a fixed punch mounted thereon, an element substantially surrounding said punch and having a recess extending across its upper face in alignment with said punch for receiving and supporting, in cooperation with said punch, an article movable longitudinally thereinto, means for resiliently elevating said element to a normal position above said punch to receive in said slot an article, an air exhaust duct carried by said element and communicating with said slot, a stationary air exhaust duct upon which said first duct reciprocates and in constant communication therewith

through which all waste material resulting from the working of an article is sucked by air, said ducts having cooperating guideways and guides, a movable ram, and a die carried by said ram and cooperating with said punch to work the article, said die during its operative movement being arranged to engage the upper face of said element to depress the same and to close the slot thereof across its top, thus increasing the effectiveness of the air exhaust through said ducts.

10. In an article trimming and working apparatus, a stationary base, a fixed punch mounted thereon, an element so constructed and arranged relative to and cooperating with said punch to form a nest open at opposite ends for receiving and supporting an article movable longitudinally thereto from one end of said nest, means for resiliently elevating said element to a normal position relative to said punch to form said nest, an air exhaust duct carried by said element communicating with said nest, a stationary air exhaust duct cooperating with said first duct and in constant communication therewith through which all waste material resulting from the working of the article is sucked by air, said punch having formed therein a channel through which a blast of air is directed to blow waste material therefrom whereby it may be sucked by air through said ducts, a movable ram, and a die carried by said ram and cooperating with said punch to work the article.

11. In an article working apparatus, a stationary support, a fixed punch mounted thereon, an element so constructed and arranged relative to and cooperating with said punch to form a nest for receiving and supporting an article movable longitudinally thereto, means for yieldably maintaining said element in a normal position relative to said punch to form said nest, an upper face on said punch to provide a support for the article before it is worked, a movable ram, and

a die carried by said ram and cooperating with said punch to work the nested article.

12. In an article working apparatus, a stationary support, a fixed punch mounted thereon, an element substantially surrounding said punch, means for yieldably maintaining said element in a normal position relative to said punch to form, in cooperation with said punch, a nest for receiving and supporting an article movable longitudinally thereto, said element and said punch having surfaces lying in a common plane in the normal position of said element upon which the article is supported, a movable ram, and a die carried by said ram and cooperating with said punch to work the nested article.

13. In an article working apparatus, a stationary support, a fixed punch mounted thereon, an element substantially surrounding said punch, means for yieldably maintaining said element in a normal position relative to said punch to form, in cooperation with said punch, a nest for receiving and supporting an article movable longitudinally thereto, said element and said punch having surfaces lying in a common plane in the normal position of said element upon which the article is supported, a movable ram, and a die carried by said ram effective during its operative movement to cause movement of said element to permit the die, in cooperation with said punch, to work the nested article.
